TREATMENT OF HYDROCARBON OILS

Joseph G. Aither, Chicago, Ill., assignor to Universal Oil Products Company, Chicago, Ill., a corporation of South Dakota

Application March 30, 1932, Serial No. 601,968

1. Claim. (Cl. 196—94)

This invention relates to the treatment of hydrocarbon oils and refers more particularly to an improved process and apparatus for the conversion of hydrocarbon oils to produce maximum yields of good quality motor fuel.

In a process for the conversion of hydrocarbon oils wherein the oil is subjected to cracking temperature and substantial superatmospheric pressure in a heating element, the total products thence passed through an unheated reaction zone wherein conversion, particularly of the vaporous products, may continue, vaporous and non-vaporous products being simultaneously withdrawn from the reaction zone to a reduced pressure vaporizing zone where their final separation occurs, vapors from the vaporizing zone being subjected to fractionation, their relatively heavy components, condensed by such fractionation, being returned to the heating element for further conversion while their lighter desirable components, withdrawn from the fractionator as vapors, are condensed and collected; the present invention incorporates the improvement which comprises subjecting said relatively light desirable components of the vapors during fractionation to the action of steam which is introduced into the fractionator at a point between the point of removal of an intermediate product as a side stream of distillate from the fractionator and the point of removal of the overhead vaporous products which comprise said desirable light distillate and gas.

It is the primary object of the invention to subject the light distillate products of conversion to the refining and cleansing action of steam while they are still in a vaporous state and during their fractionation to permit the removal of a product of good color, odor and stability direct from the cracking system. Inasmuch as the type of cracking process to which the principles of the present invention are here applied is one which produces high yields of motor fuel of the desired boiling range and of high anti-knock value, maximum yields of high anti-knock finished motor fuel requiring no further treatment may result from the unique combination.

It is often desirable in the practice of the present invention to withdraw, from the fractionator of the system, a side stream of distillate which may be reformed under cracking conditions and/or otherwise treated to produce additional yields of good quality motor fuel, or simply to improve its quality. When this type of operation is employed an additional advantage may result in the use of steam in the fractionator by intro-

ducing all or a portion of the steam into an accumulated pool of distillate in the fractionator, which distillate after being subjected to the re-boiling action of the steam to free it of entrained desirable low boiling constituents, is withdrawn as the stabilized side stream. 5

The attached diagrammatic drawing illustrates a specific form of apparatus embodying the features of the present invention. Raw oil charging stock for the process may be supplied through line 1 and valve 2 to pump 3 from which it is fed through line 4 and valve 5 to heating element 6. When desired, the raw oil may be preheated in any well known manner, not illustrated in the drawing, for example, by indirect contact with hot vaporous or liquid products of the process prior to its introduction into the heating element.

Heating element 6 is located in a furnace 7 capable of supplying the required heat to effect conversion of the oil. The heated oil is discharged from the heating element through line 8 and valve 9 into reaction chamber 10. The heating element and reaction chamber are both preferably maintained at substantially superatmospheric pressure. The total conversion products from the heating element pass through chamber 10 where particularly the vaporous products are subjected to continued conversion while the liquid products, which pass more rapidly through the chamber, are withdrawn therefrom without prolonged further conversion. Both liquid and vaporous products are withdrawn from chamber 10 through line 11 and valve 12 and are introduced into vaporizing chamber 13. 20 25 30 35

By means of valve 12, the pressure is reduced upon the products passing to chamber 13 and by virtue of the pressure reduction, heat is liberated and the liquid products are subjected to further vaporization. The residual liquid products of the process remaining unvaporized in chamber 14 40 45 50 55 may be withdrawn therefrom through line 14 and valve 15 to cooling and storage or to any desired further treatment.

Vapors from chamber 13 pass through line 16 and valve 17 to fractionation in fractionator 18, 45 the insufficiently converted relatively heavy components of the vapors condensed within the fractionator collecting in the lower portion thereof to be withdrawn through line 19 and valve 20 to pump 21 from which they are returned through line 22, valve 23 and line 4 to further conversion in heating element 6, together with the raw oil charging stock. The light distillate product of the system of the desired end boiling point is withdrawn as vapors from the upper portion of 50 55

the fractionator and steam is introduced thereto, while the product is still in a vaporous state, in the upper portion of the fractionator through line 24 and valve 25, exerting a purifying and 5 cleansing action upon the vapors in their final stages of fractionation in order to accomplish their removal from the system as a finished motor fuel. The vapors pass from the upper portion of the fractionator through line 26 and valve 27 to condensation and cooling in condenser 28, products from which are withdrawn from line 29 and valve 30 to be collected in receiver 31. Uncondensable gas may be released from the receiver through line 32 and valve 33. The finished motor 10 fuel product is withdrawn through line 34 and valve 35. The steam is withdrawn from the fractionator with the vapors condensed in condenser 28 and may be removed as water from the receiver through line 36 and valve 37.

15 It is often desirable in this type of operation to withdraw the total motor fuel product of the system in two streams which are separated in the fractionator. The overhead stream or vapors comprise the relatively light motor fuel components which are of sufficiently good quality with respect to anti-knock value, sulphur content, etc., to require no further treatment and which, in the present invention, have been subjected to the action of steam to assist in their 20 refining. That portion of the motor fuel condensed in the fractionator and removed therefrom as a side stream comprises its heavier components which may require further treatment. This condensate may collect upon a suitable tray 25 or baffle 38 in the fractionator to be withdrawn therefrom through line 39 and valve 40. As a special feature of the invention, all or any portion of the steam utilized in the fractionator may be introduced through line 24' and valve 25' 30 into the pool of condensate accumulated on tray 38, serving the purpose of reboiling this material to free it of entrained desirable light components. In case the feature of utilizing steam for reboiling of the distillate side stream is not utilized 35 it will ordinarily be necessary to employ a side stripping column 41 to which the side stream may be supplied through line 39 and valve 40. By means of a reboiling coil 42, utilizing steam or other suitable heating medium, the flow of which 40 is controlled by valves 43 and 44, reboiling of the side stream may be accomplished in column 41. The vaporized components of the distillate and side stream may be returned from column 41 to the fractionator through line 45 and valve 46. 45 The stabilized distillate may be removed through line 47 and valve 48 to any desired further treatment.

Conversion temperatures of the order of 850 to 60 1000° F. may be employed at the outlet from the heating element with superatmospheric pressures ranging, for example from 100 to 800 pounds or thereabouts per square inch. Substantially this 65 same range of pressures may be employed in the reaction chamber while the vaporizing chamber and the succeeding fractionating, condensing and collecting portions of the system are preferably operated at substantially reduced pressure

relative to that employed in the reaction chamber, ranging from approximately 100 pounds per square inch down to substantially atmospheric pressure.

As a specific example of the operation of the process of the present invention, the raw oil charging stock is a 44° A. P. I. gravity Pennsylvania distillate which is subjected together with reflux condensate, from the lower portion of the fractionator to a temperature of about 950° F. at 10 the outlet from the heating element, a pressure of approximately 400 pounds per square inch is maintained in the heating element and reaction chamber. The vaporizing chamber is maintained under a reduced pressure of approximately 15 15 pounds per square inch which is substantially equalized in the succeeding portions of the system. The overhead product withdrawn from the fractionator as vapors may represent about 57% of the charging stock. Its boiling range is approximately 20 87 to 300° F., the color is approximately 30 and the anti-knock value is equivalent to an octane number of approximately 88. The heavier motor fuel fractions withdrawn as the side stream from the fractionator comprises material boiling 25 between approximately 300 to 400° F. This material represents about 20% of the charging stock and is subjected to light sulphuric acid treatment before being blended with the lighter motor fuel fractions. The steam utilized in the fractionator 30 is introduced into the pool of condensate in the fractionator which is subsequently withdrawn as the side stream. The only other products of the system are uncondensable gas, a relatively small amount of heavy residual oil and a negligible 35 amount of coke.

I claim as my invention:

A process for producing good quality motor fuel distillate which comprises cracking hydrocarbon oil and separating resultant vapors from 40 residue, introducing the vapors to a fractionating column and fractionating the same in the lower portion of the column to condense fractions thereof heavier than gasoline, returning said fractions from the lower portion of the column to the cracking 45 step, further fractionating the vapors in the upper portion of the column to form a lighter condensate containing a substantial quantity of the heavy gasoline hydrocarbons while retaining the light gasoline hydrocarbons in vapor form in 50 this part of the column, collecting said lighter condensate at an intermediate point in the column and withdrawing the same therefrom to a stripping zone, introducing steam to the upper portion of the column above the collected lighter condensate and commingling the same therein with the vapors of said light gasoline hydrocarbons, reboiling said lighter condensate in the stripping zone and returning the resultant vapors to the column above the point of introduction of the 60 steam, removing the reboiled lighter condensate from the stripping zone and the steam-treated light gasoline vapors from the top of the column, condensing the withdrawn mixture of steam and light gasoline vapors and separating the hydrocarbon condensate from the water. 65
